UNITED STATES PATENT OFFICE.

EDGAR C. RIEBE, OF PARIS, FRANCE.

METHOD OF AND MACHINE FOR FORMING SEAMLESS TUBING.

Application filed June 18, 1925. Serial No. 38,115.

My invention relates to the manufacture of seamless tubing, and it consists in the combinations, constructions and arrangements herein described and claimed.

6 An object of the invention is the provision of a machine and method whereby seamless tubing can be made directly from molten metal.

10 A further object of the invention is the provision of a machine and method whereby seamless tubing can be formed accurately in less time for a tube of the same size than is possible by means of any machine and method known prior to the invention.

15 A still further object of the invention is the provision of a machine and method whereby a seamless metallic tube can be accurately formed to have a less inner diameter than is possible by means of any prior machine or method.

Other objects and advantages of the invention will be apparent from the following description, considered in conjunction with the accompanying drawings, in which

20 Figure 1 is a view mainly in side elevation and partly in vertical section, showing a machine embodying the invention,

Figure 2 is an end view of the structure exhibited in Figure 1,

25 Figure 3 is a plan view of a portion of the machine exhibited in Figures 1 and 2, and

Figure 4 is a perspective view of the mandrel of the machine.

The supporting structure of the machine 30 comprises a base 1 which is rigidly secured to a foundation 2 or is supported in any other suitable known manner. The base 1 is formed with a pair of upstanding portions 3 and 4 respectively spaced longitudinally of the 35 base, the upstanding portion 3 being shown as being located at one end of the base while the upstanding portion 4 is located intermediate the length of the base.

The upstanding supporting portions 3 and 45 4 carry horizontally aligned bearings 5, 6 respectively through which a shaft or tree 7 extends and by means of which the shaft or tree 7 is rotatably supported. A bracket 8 is secured on the base 1 adjacent the end of the 50 latter which is opposite the upstanding portion 3. This bracket 8 has an upstanding

plate portion 9 formed with an opening 10 in axial alignment with the shaft 7 and close to the adjacent end of the latter. A tubular matrix 11 has a flange 12 at its inner end secured by fastening devices such as the bolts and nuts indicated at 13 to the upstanding plate portion 9 of the bracket 8 so that the bore of the matrix 11 is in axial alignment with the opening 10 and an opening 14 in the body of the matrix 11 is at the upper side of the latter. A hopper 15 having a lining 16 of refractory material is supported on the base by means of standards 17 in position to discharge through the opening 14 into the space within the tubular matrix 11.

55 A mandrel indicated generally at 18 comprises a relatively large bearing portion 19 which is journaled in the inner end portion of the tubular matrix 11, whereby the mandrel will be rotatably supported in concentric relation to the tubular matrix. The mandrel 18 is connected detachably to the shaft 7 to rotate with the latter when the shaft 7 is rotated in one direction by means of a reduced 60 threaded inner end portion 20 of the mandrel which protrudes from the opening 10 of the supporting plate 9 beyond the inner face of the plate 9 and is engaged with a threaded axial socket 21 in the adjacent end of the shaft 7. The major portion of the mandrel 18, indicated at 22, extends from the bearing portion 19 to the outer end of the mandrel and is of less diameter than the bearing portion 19, whereby the portion 22 of the mandrel will be disposed in spaced concentric relation to the inner wall of the tubular matrix 11. The portion 22 of the mandrel is formed with a network of ridges, comprising a 65 threadlike ridge 23 having convolutions of the slight pitch extending spirally of the mandrel from the outer end of the portion 22 to the bearing portion 19 and spaced ridges 24 which extend longitudinally of the portion 22 of the mandrel and intersect the convolutions of the thread-like ridge 23.

70 The mandrel 18 is provided with an axial bore 25 which extends the entire length thereof and is in alignment and communication with a bore 26 which extends axially through 75 the shaft 7. The end portion of the shaft 7 which is remote from the mandrel 18 may

be reduced as indicated at 27 and is received in a stuffing box 28. The latter may be supported on an end shelf 29 at the upper end of the supporting portion 23 of the base and 5 includes a combined packing gland and coupling plate 30 having a nipple 31 at its outer side in communication through an opening 32 with a tubular boss 33 at its inner side, the reduced end portion 27 of the shaft 7 10 terminating in the tubular boss 33, whereby the nipple 31 will be in communication with the bore 26 of the shaft 7. A conduit 34 has an end portion secured on the nipple 31 and is adapted to conduct compressed air 15 from any suitable source of supply to the bore of the shaft 7 and thence to the bore of the mandrel 18 for a purpose to be presently stated.

From the foregoing description of the various parts of the device, the operation thereof may be readily understood. The shaft 7 may be rotated in the direction indicated by the arrow in Figure 1 in any suitable known manner as by means of a 20 torque imparted thereto from a motor, not shown, through suitable motion transmission mechanism, not shown, to the pulley 35. The mandrel 18 and the tubular matrix 11 are made of heat resistant steel or like 25 metal. The mandrel and the matrix first are heated in any suitable known manner, the shaft 7 then is rotated in the direction indicated and then molten metal from which a length of seamless tubing is to be made 30 is poured through the hopper 15 into the space between the mandrel and the inner wall of the matrix. The rough outer surface of the portion 22 of the mandrel will engage with the molten metal as the mandrel rotates and the molten metal will be 35 pushed in the form of a tube 36 from the free end of the matrix 11. Compressed air passes through the shaft 7 and the mandrel 18 into the tube 36 as the latter is pushed from the mandrel beyond the free end of the matrix 11 and assures quick hardening and cooling of the body of the tube 36. A suitable conveyor, not shown, such as an 40 endless chain conveyor preferably is provided at the free end of the matrix 11 for supporting the tube 36 as it is pushed from the matrix and for moving the tube 36 axially from the matrix without permitting any lateral stress on the tube 36. In the 45 event that the shaft 7 is driven by direct connection with driving means carried by the base 1, the shaft 7 and the matrix 11 may be inclined downwardly toward the free end of the latter and a chain conveyor or the like may be dispensed with, the tube 36 sliding along a trough in an inclined table, not shown, which may be provided at the free end of the matrix.

The thickness of the tube that is to be formed of molten metal in the manner de-

scribed will vary according to the difference between the outer diameter of the portion 22 of the mandrel and the inner diameter of the matrix and the outer diameter of the tube that is to be formed will vary according to the inner diameter of the matrix 11, whereby a length of seamless tubing of any desired size may be formed by selecting a matrix and mandrel of suitable diameters. The mandrel may be rotated at any desirable speed, which may vary according to the outer diameter of the length of seamless tubing which is to be formed as a result of a particular operation of the machine.

I claim:—

1. A machine for use in forming seamless metal tubing comprising a tubular matrix having a feed opening for molten metal in its upper side, a mandrel mounted to rotate in said matrix, said mandrel and said matrix being cooperatively formed to close the bore of the matrix at one end of the latter, said mandrel having a portion extending in the matrix past said feed opening in spaced concentric relation to the inner wall of the matrix, said portion of the mandrel having means on its periphery operable on rotation of the mandrel to force metal from the space between the mandrel and the matrix from one end of the matrix in the form of a tube, said mandrel having an axial bore extending the full length of the mandrel.

2. A machine for use in forming seamless metal tubing comprising a tubular matrix having a feed opening for molten metal in its upper side, a mandrel mounted to rotate in said matrix, said mandrel and said matrix being cooperatively formed to close the bore of the matrix at one end of the latter, said mandrel having a portion extending in the matrix past said feed opening in spaced concentric relation to the inner wall of the matrix, said portion of the mandrel having a thread on its periphery extending spirally in convolutions of slight pitch and adapted when the mandrel is rotated to engage with the molten metal and to push the molten metal from the matrix in the form of a tube, said mandrel having an axial bore through which compressed air may be forced and discharged from said extending end of the mandrel.

3. A machine for use in forming seamless metal tubing comprising a tubular matrix having a feed opening for molten metal in its upper side, a mandrel having a bearing portion journaled in the end portion of the matrix and having a reduced end portion extending past said feed opening in spaced parallel relation to the inner wall of the matrix, said mandrel having an axial bore, a drive shaft coupled endwise to said mandrel, said drive shaft having an axial bore in alignment with the bore of the mandrel, and means associated with the end portion of said

shaft which is remote from said mandrel for supplying compressed air to the bore of said shaft, as and for the purpose described.

4. The herein described method of forming seamless metal tubing which comprises feeding molten metal to the space between two spaced concentric tubular members so

that the metal will be forced in tubular form from said space at one end of the space, and then forcing air through the inner tubular member into the tube that is forced from said space. 10

EDGAR C. RIEBE.
